US0D1109773S

(12) **United States Design Patent** (10) Patent No.: **US D1,109,773 S**
(45) Date of Patent: ** Jan. 20, 2026

(54) **DISPLAY SCREEN OR PORTION THEREOF
WITH A COMPUTER GENERATED ICON**

(71) Applicant: **Wenobs. Co., Ltd.**, Jeju-si (KR)

(72) Inventor: **Hwa Jeong Lee**, Jeju-si (KR)

(73) Assignee: **Wenobs. Co., Ltd.**, Jeju-si (KR)

(**) Term: **15 Years**

(21) Appl. No.: **29/953,443**

(22) Filed: **Jul. 22, 2024**

(30) **Foreign Application Priority Data**

Mar. 15, 2024 (KR) 30-2024-0010090

(51) **LOC (15) Cl.** **14-04**

(52) **U.S. Cl.**

USPC **D14/489**

(57) **CLAIM**

The ornamental design for a display screen or portion thereof with a computer generated icon, as shown and described.

DESCRIPTION

The sole FIGURE is a front view of a display screen or portion thereof with a computer generated icon, showing my new design.

The dash-dash broken lines depict portions of the display screen or portion thereof with a computer generated icon that form no part of the claimed design. The dot-dash broken lines depict boundaries that form no part of the claimed design.

1 Claim, 1 Drawing Sheet
